UNITED STATES PATENT OFFICE.

FLOYD J. METZGER, OF NEW YORK, N. Y., ASSIGNOR TO AIR REDUCTION COMPANY, INC., A CORPORATION OF NEW YORK.

APPARATUS FOR MANUFACTURE OF ALKALI-METAL CYANID.

1,358,014.

Specification of Letters Patent.

Patented Nov. 9, 1920.

Original application filed March 16, 1918, Serial No. 222,812. Divided and this application filed December 5, 1918. Serial No. 265,388.

To all whom it may concern:

Be it known that I, FLOYD J. METZGER, a citizen of the United States, residing at New York city, in the county of New York, State 5 of New York, have invented certain new and useful Improvements in Apparatus for Manufacture of Alkali-Metal Cyanid; and I do hereby declare the following to be a full, clear, and exact description of the invention, such as will enable others skilled in the art to which it appertains to make and use the same.

The present invention relates to the production of alkali metal cyanids, and more 15 particularly to an apparatus adapted for use in carrying out the method described in my co-pending application Serial No. 222,812, filed March 16, 1918, of which the present application is a division.

20 The process referred to involves the treatment of mixtures of alkali metal carbonates or alkali metal hydroxids (or both) together with coke, charcoal or equivalent carbonaceous material, and with or without the 25 addition of catalytic material such as iron, the operation being conducted at an elevated temperature and in the presence of nitrogen or a nitrogen-containing gas.

While the reactions involved in this 30 general procedure are well known, various practical difficulties have been encountered in such endeavors as have been heretofore made to introduce the process into commercial use. For instance, in order to bring 35 about the fixation of the nitrogen for the production of cyanid in such processes, it is necessary, as above indicated, to maintain a high temperature (approximately 850° C.-1000° C.) which, of itself, introduces complications in the construction and 40 maintenance of the apparatus employed. So also, at the temperature necessary for reaction, the alkali metal carbonate or hydroxid (or both), are in a molten or semi-fluid condition, so that the entire furnace charge is 45 more or less plastic, in which state it opposes serious obstacles to the well-distributed contact between the nitrogen gas and the furnace charge, necessary for an efficient and 50 uniform procedure.

Heretofore, the endeavor to realize an industrial utilization of the general process has encountered the notable obstacle that

the semi-plastic charge adheres, to a large extent, to the inner walls of the furnace, 55 in the absence of any provision for preventing such adhesion. To meet this objection, it has been proposed, for example, to maintain a protective layer of coke or other carbonaceous material (not containing alkali) 60 of variable thickness, adjacent to the furnace walls, so as to prevent the plastic or semi-plastic furnace charge from coming in actual contact with the furnace walls themselves. So far as I am aware, however, this 65 and like expedients have not been attended with satisfactory results, and, in fact, introduce additional complications interfering with the simplicity and economy of operation desirable in carrying out the process. 70

It may be noted further, that the cause of failure, from an industrial standpoint, in many of the proposals heretofore made, has probably been due to the fact that during the operation the furnace charge shrinks 75 to a very great extent (the amount of shrinkage, of course, depending upon the nature and proportion of the ingredients entering into the composition of the charge) and may amount to as much as one-third or more of 80 its original volume. During this shrinking, the contents of the furnace become channeled and this channeling allows the nitrogen gas to pass through the furnace charge 85 with a corresponding diminution of the desired contact, and with a resultant low and irregular yield of the alkali metal cyanid desired.

The present invention provides a mode of 90 operation, which, in overcoming the difficulties hereinbefore referred to, supplies a satisfactory solution of the industrial or commercial problem of producing alkali metal cyanids from mixtures of the general character appropriate to that manufacture. 95

The accompanying drawing illustrates 100 the preferred form of apparatus involved in the practice of the invention, the structure being shown partly in side elevation and partly in section.

Referring to the drawing, 2 represents 105 conventionally any suitable heating furnace, provided with a grate 3, fuel charging door 4, ash pit door 5, baffles 6, and stack 7. The details of this furnace structure may be chosen to provide the desired heating effect,

and may be widely varied, as will be understood by those skilled in the art.

Extending through the furnace is a cylindrical metal tube 1, preferably of an alloy containing essentially nickel, chromium and iron, with or without small quantities of manganese, silicon, etc., the relative proportions of the constituents of the alloy being such that the tube will withstand, to a satisfactory degree, the action of the furnace gases at the required comparatively high temperature. In practice, I prefer to employ a tube of approximately 15 inches internal diameter, and of a length of about 15 ten feet for that portion of the tube which traverses the heating zone of the furnace. The upper and lower ends of the tube, outside of the furnace, may be of metal of less cost, such as iron, so as to diminish the expense of the structure.

The metal tube or retort 1, is carried on roller thrust bearings 8, on which it can be rotated, these bearings being suitably mounted to efficiently sustain the weight imposed upon them. The angular inclination of the tubular retort may be varied more or less in accordance with the nature, both chemical and physical, of the mixture making up the charge,—a suitable angle being, for instance the angle shown in the drawing. The upper end of the tube 1 is provided with a conveyer 13 discharging into an elbow pipe 12, whereby the retort can be fed with the furnace charge automatically, and continuously or intermittently, as may be desired. The lower end of the tubular retort is provided with a gear 9 driven by the gear 10 from the driving shaft gear 11, or the like, so as to rotate the tubular retort at the rate desired, suitable means (not shown) being provided for varying the speed of rotation.

The lower end of the tubular retort 1 is received within a stationary casing 14 closed at its upper end, suitable packing being provided, as shown at 15, to prevent the escape of gas at the joint between the stationary casing and the rotatable retort. A discharge screw 16 projects into the lower end 50 of the tubular retort 1; it is carried by a shaft 17 which passes through the casing 14 and is driven from any suitable source of power by the bevel gears 18. The casing 14 is provided with a discharge hopper 19 depending therefrom, and at the lower end of the hopper is a discharge valve 20 by which the treated charge received from the retort may be discharged without permitting the escape of gases from the casing and without admitting atmospheric air therethrough.

The nitrogen or nitrogen-containing gases are admitted to one end of the tubular retort and pass through the charge therein, and the reaction gases are allowed to escape 65 at the opposite end. In the drawing, a pipe

for the inlet of the nitrogen or nitrogen-containing gases is shown at 21, connected to the stationary casing 14. At the opposite end of the tubular retort, the reaction gases may be allowed to escape through the feeding devices for the charge, or otherwise, as may be desired.

In the use of the apparatus, the charge, consisting of a suitable mixture of alkali metal carbonate or alkali metal hydroxide 75 (or both) and coke, charcoal, or other carbonaceous material, with or without a catalyst, such as iron, is fed into the upper part of the tubular retort 1, which portion of the retort constitutes a preheating zone for the 80 charge. From the preheating zone, the mixture passes through the reaction zone within the walls of the furnace, and thence into the cooling zone, that is to say, the lower portion of the retort projecting beyond the 85 furnace wall. The charge is finally withdrawn from the retort, with the assistance of the discharge screw 16, and drops into the hopper 19 from which it may be removed, as desired, by the discharge valve 20.

The operation is preferably a continuous one, the retort being maintained substantially filled with the charge throughout the operation, and the rate of discharge of the furnace charge being determined by the operation of the discharge screw 16. The retort, with the furnace charge therein, is rotated continuously by means of the driving gear and, at the same time, the nitrogen or nitrogen-containing gases are admitted to 100 the cooling zone of the retort from the conduit 21.

The nitrogen or nitrogen-containing gases pass up through the portion of the charge in the cooling zone, and take up heat therefrom, so that the gases are preheated before they enter the reaction zone of the retort. So also, the temperature of the treated charge is reduced by the cooling effect of the nitrogen or nitrogen-containing gases.

Within the reaction zone of the tubular retort, the charge is thoroughly agitated by the rotation of the retort, thereby effectually preventing caking of the charge and adherence thereof to the walls of the retort and also preventing the formation of channels or fissures through the charge. Within this reaction zone, the charge, although reduced to a pasty or semi-plastic condition, is thus presented to the best advantage to uniform 12 and well-distributed contact with the reaction gases, so that a correspondingly high and regular yield of alkali metal cyanide results.

The upper end of the retort, constituting 12 the preheating zone beyond the furnace walls, being more or less filled with the incoming charge, serves as a condenser for any volatile product or fume carried along out of the reaction zone, and the incoming 13

charge is, at the same time preheated by means of the outgoing hot gases which pass through it.

As the charge shrinks in the reaction zone 5 of the retort, the shrinkage is continuously and automatically taken care of by the supply of charge from the preheating zone, so that the reaction zone is kept completely filled. From the reaction zone, the treated 10 charge, still in a plastic or semi-fluid condition, enters continuously the cooling zone, and immediately begins to solidify. In so doing, the rotation of the tubular retort causes the material to become nodulized into 15 lumps or nodules of relatively small size, particularly appropriate to the subsequent use for which the treated charge is especially intended, that is to say, as the means for obtaining ammonia by the passage of 20 steam therethrough or the extraction of cyanid therefrom. The exit of the charge from the cooling zone is assisted and regulated, as hereinbefore noted, by the conveyor screw 16, which may be operated continuously or intermittently, as desired. 25

It will be apparent that, instead of operating the entire process continuously, as preferred in most cases, the apparatus is likewise well adapted for operation intermittently, that is to say, by supplying it with a given amount of furnace charge, treating and discharging the same in its entirety, and then supplying its place with a succeeding batch to be treated. The nitrogenous gas, 30 (whether nitrogen *per se*, or a gas or mixture of gases containing nitrogen) may be obtained from any desired and suitable source as will be well understood by those skilled in the art.

Having thus described my invention, what I claim is:

1. An apparatus for the production of alkali metal cyanids by the treatment of a mixture of an alkali and a carbonaceous material, with a nitrogenous gas, comprising the combination of a tubular retort mounted at an incline to the horizontal, a furnace inclosing a portion of the retort intermediate the ends thereof, said portion constituting the reaction zone of the retort, the lower portion of the retort extending beyond the furnace and providing a cooler nodulizing zone for the product, means for rotating the retort on its axis, feeding devices for feeding the charge to the upper end of the retort, and a conduit communicating with the lower end of the retort for the introduction of nitrogen gas.
2. An apparatus for the production of alkali metal cyanids by the treatment of a mixture of an alkali and a carbonaceous material with a nitrogenous gas, comprising

the combination of a tubular retort mounted at an incline to the horizontal, a furnace inclosing a portion of the retort intermediate 65 the ends thereof, means for rotating the retort on its axis, feeding devices for feeding the charge to the upper end of the retort, means for assisting the discharge of the treated material from the lower end of the 70 retort, and a conduit communicating with one end of the retort for the introduction of the nitrogenous gas; substantially as described.

3. An apparatus for the production of 75 alkali metal cyanids by the treatment of a mixture of an alkali and a carbonaceous material with a nitrogenous gas, comprising the combination of a tubular retort mounted at an incline to the horizontal, a furnace inclosing a portion of the retort intermediate 80 the ends thereof, means for rotating the retort on its axis, feeding devices for feeding the charge to the upper end of the retort, means for assisting the discharge of the 85 treated material from the lower end of the retort, said means consisting of a discharge screw, and a conduit communicating with one end of the retort for the introduction of the nitrogenous gas; substantially as de- 90 scribed.

4. An apparatus for the production of alkali metal cyanids by the treatment of a mixture of an alkali and a carbonaceous material with a nitrogenous gas, comprising 95 the combination of a tubular retort mounted at an incline to the horizontal, a furnace inclosing a portion of the retort intermediate the ends thereof, said portion constituting the reaction zone of the retort, means for rotating the retort on its axis, feeding devices for feeding the charge to the upper end of the retort, a closed casing spaced from the furnace and connected to the reaction zone by a portion of the retort which provides a 105 cooling zone, and a conduit connected with the casing for the introduction of the nitrogenous gas; substantially as described.

5. An apparatus for the production of alkali metal cyanids by the treatment of a 110 mixture of an alkali metal compound and a carbonaceous material with a notrogenous gas, comprising the combination of an inclined tubular retort, a furnace inclosing a portion of the retort intermediate its ends, 115 means for rotating the retort about its axis, means for feeding the charge to the upper end of the retort, means for assisting the discharge of the treated material from the lower end of the retort and means for introducing nitrogenous gas to the retort.

In testimony whereof I affix my signature.

FLOYD J. METZGER
